UNITED STATES PATENT OFFICE

CHARLES F. SPERY, OF CHICAGO, ILLINOIS

METER FOR WASHING AND LIKE MACHINES

Application filed April 25, 1927. Serial No. 186,236.

This invention relates to meters for electrically operated domestic washing machines.

In metered washing machines as heretofore employed, the meters are coin controlled, and 5 the machine runs only as long as the time allowed for the value of the particular coin dropped into the meter. This time is relatively short and usually several coins must be dropped into the meter before a washing 10 is completed. Even then the machine may run longer than required to complete the washing so that the user is required to pay for this overtime.

In my copending application Serial No. 15 177,130, filed March 21, 1927, now Patent No. 1,801,618, granted April 21, 1931, I have disclosed and claimed a meter which is key operated and not coin operated and through 20 which the washing machine may be turned on and off at the will of the user, and thus restrict the charge for the use of the machine to the actual time the machine is operated and no more. For a number of users of a single machine, the meter is provided with 25 as many time registering units as there are users for the machine, for example six, with different keys for the several units so that the respective users can operate the machine only through their respective units and no 30 others.

In my copending application, it is contemplated to operate the meter thereof by an electric motor which is separate and distinct from the motor which operates the washing 35 machine. This is not objectionable but from the standpoint of economy of construction and operation is not desirable because two motors are required, one for the meter and the other for the washing machine. Furthermore, in my previous construction two 40 key operable means are employed, one for the meter and the other for the motor switch. This is also not objectionable, but it requires each user of the machine to manipulate two 45 keys before the meter and the washing machine can be set in operation.

The main object of my present invention is to provide a meter which is an improvement on the one of my other application.

50 To accomplish this, I provide, among other

things, a meter so constructed that it may be connected with and operated by the motor of the washing machine and thus save the cost and maintenance of an additional motor as employed in my former construction.

Another object of my present invention is to require each user to manipulate but a single key for starting and stopping the meter and the motor, respectively, and thus avoid the use of two keys, as in my previous construction.

A further object of my present invention is to allow the user by a single key to start and stop the meter and the washing machine simultaneously, so that no opportunity is afforded for the meter to continue to operate after the washing machine has been stopped to register against the user more than the actual time the washing machine was in 70 operation.

Other and further objects of my invention will appear from the following specification, taken in connection with the accompanying drawings, in which—

Fig. 1 shows a domestic type of washing machine equipped with a meter of my invention;

Fig. 2 is a front view of the meter, the cover being broken away to show the interior mechanism;

Fig. 3 is a vertical sectional view taken on line 3—3 of Fig. 2;

Fig. 4 is a horizontal sectional view taken on line 4—4 of Fig. 2; and

Fig. 5 is a front view of one of the key operable locks with which the meter is provided.

In Fig. 1, 1 indicates a domestic washing machine electrically operated by an electric motor 2 mounted on the frame of the machine. The motor 2 is arranged with its armature shaft horizontal and connected by suitable gearing with the agitator or equivalent member (not shown) in the tub or washing compartment of the machine. The armature shaft of the motor is provided with an extension 3 supported at its outer end in a hanger 4 depending from the frame of the machine. At the hanger 4, the extension 3 has a bevel pinion 5 in mesh with a bevel

gear 6 on the lower end of a vertical shaft 7 which extends into the box or casing 8 of the meter which is rigidly secured to the horizontal frame section 9 of the machine, as shown in Fig. 1. By the drive shown and described, the operative parts of the meter are driven by the motor 2 of the machine 1, and thus a separate motor to operate the meter is not required.

The box or casing 8 of the meter is preferably made rectangular in shape, and has enclosing walls, 10 being the rear wall and 11 the front wall, the latter being in the form of a cover which is hinged to the top wall 12 of the box, as shown in Fig. 3. Any suitable form of lock may be employed for locking the cover 11 in closed position so that unauthorized persons may not open the box to tamper with the meter mechanism or the switch for the motor, which is also enclosed within said box. In Fig. 3, I have shown the lock in the form of a bar 13 extending across the bottom of the box on the inside and rigidly secured at one end to the rear wall 10. The other end of the bar extends outside of the box through a slot or opening in the cover 11 and there is apertured to receive a padlock 14 for locking the cover closed.

Located in the upper portion of the box 8 is a vertical plate 15, which is secured to the rear wall 10. Extending along this plate in front of the same is a horizontal shaft 16 journaled in a suitable number of brackets 17 which are secured to the plate 15. The shaft 16 is driven by the shaft 7 at a much slower speed by a worm 7^a on the shaft 7 in mesh with a worm gear 16^a on the shaft 16. The latter has a length to accommodate a number of registering units 18, 18, which are arranged in side by side relation along the shaft and in front of the same, as shown in Fig. 2. There four units are shown; the number, however, depending on the number of users to be accommodated by the meter. Ordinarily, the meter will contain six units to take care of six users, thus adapting the washing machine to a six-apartment building.

The units 18 are made alike, so a description of one will suffice for all. Each unit 18 comprises inner and outer vertical plates 19, 20 bolted together yet spaced by spacers on the bolts, as shown in Fig. 3. The inner plate 19 has rearwardly extending brackets 21, 21 by which the unit is secured to and spaced outward from the base plate 15.

The outer plate 20 is provided on its front face with a number of dials, preferably three, 22, 22^a, and 22^b, arranged in the order named. The dials are suitably graduated, as for example from "0" to "9" as shown. A shaft 23 extends through the center of each dial and has a pointer 24 at its outer end to travel about the dial in the rotation of the shaft. The dials are arranged with the dial 22 first

in order and nearest the right-hand end of the casing 8 as viewed in Figs. 1 and 2. The first dial registers "minutes," its hand 24 taking sixty minutes to complete one revolution about said dial. The other dials 22^a, 22^b register hours, it requiring ten hours for the hand of dial 22^a to complete one revolution about said dial, and a hundred hours for the hand of dial 22^b to go around said dial. The shafts for the hands of the several dials are journaled in the inner and outer plates 19, 20, and are connected by gears and pinions of the proper diameters and teeth to give this ratio. This part of the unit follows the construction of an ordinary domestic gas meter.

The shaft 23 of the dial 22 is made longer than the other shafts and is slidably mounted in the plates 19 and 20. The pinion 25 on this shaft is made wide enough to remain in mesh with the gear 26 on the shaft of the dial 22^a in the endwise sliding movements of the shaft 23. The latter is provided at its inner end with a cup gear 27 to the rear of the plate 19 and is moved with the shaft 23 into and out of mesh with a gear pinion 28 on the main operating shaft 16 to connect the unit to and disconnect it from said shaft.

For so moving the gear 27, I provide an arm 29 secured at its upper end to the plate 19 on the outer side thereof above the shaft 16, as shown in Fig. 3. This arm extends across the shaft 23 and there has an aperture for said shaft to pass through, as shown in Fig. 4. The hub of the pinion 25 is on one side of the arm and a collar 30 is fixed to the shaft on the opposite side of the arm so that the latter may slide the shaft endwise when the lower end of the arm is moved inward and outward, respectively.

To accomplish this, I provide for the meter unit 18 a Yale or similar lock 31 mounted in a stationary horizontal bar 32, which extends lengthwise of the box beneath the several units, as shown in Fig. 3. The bar 32 is supported just inside of the cover 11 by rods 33, which extend to the rear wall 10 of the box and are secured thereto. The casings of these locks are fixed in the bar 32 by set screws, as shown, and project out through and substantially fill openings made therefor in the cover 11 when the latter is closed.

The barrel or rotatable part 34 of the lock extends beyond the rear side of the bar 32 and there carries a radial arm or dog 35, which has a rearwardly extending lug 36 at its outer end. The arm 29 extends below the unit 18 to the rear of the lug 36 and is there shaped to have upper and lower vertical flat portions *a*, *b* out of the plane of each other and connected by an inclined joining portion *c*. This lower end of the arm 29 is made wide enough to be within the path of turning of the cooperating lug 36 so that the latter in traveling down over the inclined portion *c* will move the arm inward to move the gear 27.

into mesh with the associated pinion 28 on the main shaft 16 and thus connect the meter unit 18 thereto. A coiled spring 29* acts on the rear side of the arm 29 to hold its lower end against the lug 36 and to move the gear 27 out of mesh with its pinion 28 when the lug 36 is moved up the incline *c* of the arm.

To turn on and off the current to the washing machine motor 2, I provide a switch mechanism within the box 8. This switch is clearly shown in Fig. 2, and it comprises a vertical plate or block 37 supported from the rear or back wall 10 of the box by bolts 38, 38. A horizontal bar or slide 39 is arranged above the plate 37 and is slidably supported in position by channel shaped brackets 40, 40 depending from the rear side of the bar 32. The latter overlaps the upper portion of the slide 39 and retains the same in said brackets. The slide 39 has stops 41, 41 on its under side between the brackets so that by contact therewith the endwise movement of the slide is limited.

The slide 39 is provided in its upper edge with a number of notches 42, 42, one for each meter unit 18, that is, one for each lock 31. The outer ends of the arms 35 of the locks enter these notches as the arms are turned down and slide the bar toward the left.

A bracket 43 is secured to the under side of the slide 39, and to this bracket is pivoted a lever 44, which is drawn downward by a coiled spring 45 which has one end secured to the outer or free end of the lever. The other end of this spring is hooked over a lug 46 on the base block 37. Pivoted on the front face of the block 37 is a switch blade 47 made right-angular in shape and having the upper end of its upper or short arm pointed in the form of an inverted V. The lever 44 carries a V-shaped projection 48 insulated therefrom and which rides over the pointed upper end of said short arm to swing the long arm of the blade 47 into and out of contact with the fixed parts 49, 49 of the switch as the apexes of the V's pass over each other. The switch parts 49 are insulated from each other and from the block 37, and the blade 47 is also insulated from said block. The switch is quick snap acting and eliminates destructive arcing.

Wires 50, 51 are connected with the switch parts 47, 49, respectively, and extend out of the box 8 through the bottom wall thereof, as shown in Fig. 2. The wire 50 from the blade 47 leads to one of the terminals of the motor 2 of the washing machine. The other wire 51 from the switch members 49 leads to the source of current supply, and a third wire 52 is connected with the other terminal of the motor 2 and leads to the source of current supply so that on closing the switch blade 47 current is turned on to the motor 2 for operating both the washing machine and the meter. The wires 50 to 52 are housed in a

suitable protective casing 53, as indicated by dotted lines in Fig. 1, so that the washing machine can not be run except through the meter 8 and then only by persons having keys for the locks 31.

When the motor 2 is running, the arm 35 of the particular lock 31, which moves the slide 39 to close the motor switch, extends down into its notch 42 in the slide and the key 31* can not be withdrawn from the lock. On turning the key to raise the arm 35, the latter in its swinging movement moves the slide 39 towards the right to open the switch and permit the arm 29 of the associated unit 18 to move the gear 27 out of mesh with its pinion 28 on the shaft 16 to disconnect the unit from said shaft.

The meter of my present application is strong yet simple in construction and operation and requires the user to manipulate only one key to set both the washing machine and meter in operation.

By driving the meter by the motor which operates the washing machine, the meter may be mounted directly on the machine as a part of its equipment. With the units 18 registering the duration of time the washing machine is operated, the use of the machine is not hindered by the users not having the required coins to start the machine, as with coin controlled meters. With my improved meter, the users may be billed at stated intervals for their use of the machine, similar to gas and electric light bills.

The details of structure shown and described may be variously changed and modified without departing from the spirit and scope of my invention.

While I have shown my improved meter applied to a domestic washing machine and have described the use of the meter in that connection, it is to be of course understood that the meter could be equally as well used in connection with any other machine capable of use by a number of different persons, like an ironing machine. In the latter term, I include wringers of all types whether a part of the washing machine or not.

I claim as my invention:

1. The combination with a washing machine having an electric motor for operating the same, of a meter on the machine and having means for registering the number of hours and fractions thereof the machine is in operation, means connecting the motor to the meter for operating the same, an electric switch for the motor, and means operable by a single key for closing and opening the switch and simultaneously connecting the registering means to and disconnecting it from said motor.

2. The combination with an electrically operated washing machine, of a meter for the machine and having a unit for registering the number of hours and fractions thereof

the machine is in operation, an operating shaft for said unit, a gear fixed to said shaft, a gear slidably mounted in the unit, a spring arm connected with the unit gear for moving the same into and out of mesh with the shaft gear, and key operable means for moving said arm.

3. The combination with an electrically operated washing machine, of a meter for the machine and having a unit for registering the number of hours and fractions thereof the machine is in operation, a shaft for operating said unit, a gear fixed to said shaft, a gear in the unit, a spring arm connected with the unit gear, said arm having a bent portion forming a cam, and key operable means acting on said cam portion for meshing and unmeshing said gears.

4. The combination with an electrically operated washing machine, of a meter for the machine and having a unit for registering the number of hours and fractions thereof the machine is in operation, a shaft for operating said unit, a gear fixed to said shaft, a gear in the unit, an arm connected with said unit gear and having offset straight portions and an interposed connecting inclined portion, and key operable means having a projection movable over said straight and inclined portions, respectively, for effecting the meshing and unmeshing of said gears.

5. The combination with an electrically operated washing machine, of a meter associated with said machine and having a plurality of units for registering the number of hours and fractions thereof the machine is in operation by different users, a main operating shaft extending past the units and common thereto, a gear fixed to said shaft at each unit, a slidably mounted gear in each unit, and a single key operable means for each unit for moving by the key the slide gear of the unit into and out of mesh with the associated shaft gear.

6. A meter of the character described having a plurality of registering units having operating gears, a common operating shaft for said units, a motor connected with said shaft for operating the same, a gear on said shaft for each unit, a switch for said motor, an endwise movable bar common to said units and connected with said switch, and a single key operable means for each unit for moving one of the unit gears into and out of mesh with its associated shaft gear, each key operable means having a part to engage said bar for moving the same in opposite directions through the key for opening and closing said switch simultaneously with the meshing and unmeshing of the unit and shaft gears.

In testimony whereof I affix my signature this 18th day of April, 1927.

CHARLES F. SPERY.
